UNITED STATES PATENT OFFICE

111,030

DESIGN FOR A HANDBAG

Irving Pichel, New York, N. Y.

Application June 24, 1938, Serial No. 78,020

Term of patent 3½ years

To all whom it may concern:

Be it known that I, Irving Pichel, a citizen of the United States and resident of New York city, in the county and State of New York, have invented a new, original, and ornamental Design for a Handbag, of which the following is a specification, reference being had to the accompanying drawing, forming a part thereof, and of which Figure 1 is a front view of a handbag showing my new design; Fig. 2 is a view thereof in end elevation, and Fig. 3 is an enlarged view thereof in rear elevation.

The characteristic features of my design reside in the handbag as shown having inverted U-

shaped handles, with spaced tassel and knot elements on the upper front of the bag body in alignment with the arms of the handles, and a pair of knot elements at the rear of the bag body opposite to said elements, said tassel element being the only tassel at the front and rear of the bag body, and said knot elements being located along a horizontal plane passing approximately through the top of the tassel element.

I claim:

The ornamental design for a handbag, substantially as shown and described.

IRVING PICHEL.
